US0D1020394S

(12) **United States Design Patent** (10) **Patent No.:** **US D1,020,394 S**
(45) **Date of Patent:** **** Apr. 2, 2024**

(54) **BAG** 81/3818; B65D 81/383; F25D 2331/801;
F25D 2331/804; F25D 11/003; F25D
2323/061

(71) Applicant: **YETI Coolers, LLC**, Austin, TX (US) See application file for complete search history.

(72) Inventors: **Kyle Edward Rogers**, Austin, TX (US); **John Fritz**, Austin, TX (US); **Jeffrey Charles Munie**, Austin, TX (US)

(57) **CLAIM**

The ornamental design for a bag, as shown and described.

DESCRIPTION

FIG. 1 is a top, front, right perspective view of a bag showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, front, right perspective view of an alternative claimed configuration of a bag showing our new design. The broken lines depicting the remainder of the bag form no part of the claimed design.

1 Claim, 6 Drawing Sheets
